[57] CLAIM

The ornamental design for a container lid having a double-pour spout, as shown and described.

DESCRIPTION

FIG. 1 is a front perspective view of a container lid having a double-pour spout showing my new design;

FIG. 2 is a top plan view of the container lid of FIG. 1;

FIG. 3 is a bottom plan view of the container lid of FIG. 1;

FIG. 4 is a front elevation view of the container lid of FIG. 1;

FIG. 5 is a rear elevation view of the container lid of FIG. 1;

FIG. 6 is a left side elevation view of the container lid of FIG. 1, the right side elevation view being a mirror image of FIG. 6; and,

FIG. 7 is a perspective view of the container lid of FIG. 1 with the double-pour spout opened.
